UNITED STATES PATENT OFFICE.

MANUEL SHAMPAINTER, OF PASSAIC, NEW JERSEY.

DISPLAY-RECEPTACLE.

1,209,343.

Specification of Letters Patent. Patented Dec. 19, 1916.

Application filed September 28, 1915. Serial No. 53,112.

To all whom it may concern:

Be it known that I, MANUEL SHAMPAINTER, a citizen of the United States of America, and a resident of Passaic, in the county of 5 Passaic and State of New Jersey, have invented a certain new and useful Display- 60 Receptacle, of which the following is a specification, the same being a full, clear, and exact description of the invention, such as will 10 enable others skilled in the art to which it appertains to make and use the same.

This invention relates to cases or receptacles for articles or materials of any kind, and in particular to a box made or provided 15 with a self-contained supporting device constructed and arranged to hold the preferably open receptacle in an inclined relation.

My invention consists of an article of the 20 class described adapted to contain articles of merchandise or the like constructed and arranged substantially as hereinafter more particularly pointed out, whereby it is adapted not only to contain the desired articles and to retain them securely against loss, but 25 also to permit them to be readily withdrawn at will and to hold the same at any desired angle for exhibition or display purposes, the whole forming a unitary organization.

In the drawings, illustrative of an embodiment of the invention, which accompany and 30 form a part of this specification, Figure 1 represents an elevation of an article constructed according to my invention; the cover being shown in a partly open position 35 by dotted lines; Fig. 2 is an elevation of the said receptacle illustrated as sustained in an open relation in an inclined position; Fig. 3 is a view in detail showing the hinge joint or folding part of the box in section; Fig. 4 40 is a rear elevation of the article when in the position shown in Fig. 2; Fig. 5 is a plan view of a blank for another article in which the invention is embodied; Fig. 6 is a perspective view of the receptacle held in an 45 open relation in an inclined position; and Fig. 7 is a rear view of the same.

Like numerals of reference indicate like parts in all the views.

Referring particularly to the drawings, 50 55 denotes the body portion or receptacle proper of the box and 21 the preferably integral cover therefor. The rear portion of the cover in the instance under consideration is preferably made in sectional form, as for example comprising sections 31 and 41, the upper part 21 of the cover being preferably

attached to the section 31 in a yieldable relation as by a hinge joint 51, integral or otherwise, and the sections 31 and 41 being also preferably secured together in a movable relation, as by a hinge joint 52. The section 41 is preferably fastened to the body portion 61 of the box in a fixed and immovable relation.

In order to open the box, the cover 21 is 65 first raised to a vertical position, as indicated by dotted lines in Fig. 1, the same turning on the hinge 52, after which the cover 21 is turned downward and under the said body portion 61 until the receptacle occupies the 70 inclined position illustrated in Fig. 2, the duplex joint or hinge 51 and 52 yielding sufficiently for the successful operation of the said movement. The contents of the box may thus be displayed without requiring any 75 further manipulation, and when it is desired to close the receptacle again, as for purposes of storage or transportation, all that is necessary to be done is to restore the cover 21 to its original position, whereupon 80 the box will occupy no more room than any ordinary receptacle of the kind. The cover thus performs a double function, first to provide a closure for the box, and second, to serve as a means for supporting the body portion 85 of the same in an inclined relation for display purposes.

I sometimes desire to hold the receptacle 90 in a permanently inclined position. A convenient method of making a box to answer this purpose consists in forming up a blank, as shown in Fig. 5, by bending, or cutting and attaching, the parts 4 and 6 on the line 10, and then bending, or cutting and attaching, the side flaps 2 in an inward direction, 95 or toward each other on the line 11, and then securing the said flaps to the lower portions 3 of the side portions 5 and 7, whereupon the box will assume the position shown in Fig. 6, where it rests upon the lower edge 100 of the front face as indicated by the line 10, and also upon the lower edges of the side portions 2 and 3, and the goods to be displayed will be contained in the receptacle formed by the sides 5 and 7, the front part having an upper edge 9 and the bottom portion 4 terminating in a rear edge 8.

It is obvious that receptacles or cases comprising a unitary organization in which the parts are not separable, such as those of the kind described, may be made in other shapes than those shown, dependent upon the char-

acter of the contents desired to be held or displayed by the same, and upon the particular use to which the box is intended to be put, as for example whether the latter is 5 designed to contain material in bulk or packages. It will be noted that my device provides a closure comprising a rigid cover to overlie the entire top and upper portions of the sides of the receptacle, whereby the 10 contents of the box, when closed, may be maintained in a condition free from dust. The said cover is hinged to the box at one end of the same a considerable distance from the top thereof, as shown in Fig. 1, the other 15 hinge joint of the closure being located at the top edge of one end of the receptacle, and being held securely to the same by the friction of the wide depending side portions of the cover at that point against the sides 20 of the box. On account of the rigidity of the cover, which extends without any open cracks or yieldable portions therein across the whole top of the receptacle and fits snugly thereto, the said cover will always 25 lie close to the entire top edges of the box when in a closed relation.

The front end of the cover hangs down over the box, affording thereby not only a more secure closing of the same, but also 30 providing by the said depending portion of the closure, when in an inverted position, means to hold the box proper a distance above the support therefor, as indicated in Fig. 2, whereby the contents of the open 35 box may be kept free from accumulated dust, etc., and may also be displayed to better advantage, and also affording space for a label description of the contents of the receptacle, or for an advertising card.

40 I wish it to be understood that I do not desire to be limited to the exact details of construction shown and described herein, for

various modifications will occur to a person skilled in the art.

What I claim as my invention is:—

45 1. A receptacle comprising four sides and bottom portion, a supporting stand therefor consisting of a base having four sides and a top portion, the said four sides lying substantially in the planes of those of the receptacle, and a hinging device constructed and arranged to so attach the receptacle and base together that, when reversed in position, the four side parts of the base shall overlap the four side portions of the receptacle, and the top part of the base shall form the cover of the receptacle, thus forming a closure of the entire upper portion thereof.

50 2. A receptacle comprising four sides and bottom portion, a supporting stand therefor 55 consisting of a base having four sides and top portion, the said four sides lying substantially in the planes of those of the receptacle, one side portion of the base being less in height than its opposite one to support the receptacle at an angle, and a hinging device constructed and arranged to so attach the receptacle and base together that, when reversed in position, the four side parts 60 of the base shall overlap the four side portions of the receptacle, and the top part of the base shall form the cover of the said receptacle, thus forming a closure of the entire upper portion thereof having two 65 sides of unequal height and the other two 70 formed with inclined edges.

75 In testimony of the foregoing specification I do hereby sign the same in the city of New York, county and State of New York this 14th day of September, 1915.

MANUEL SHAMPANIER.
